UNITED STATES PATENT OFFICE.

GEORGE C. SALMONS, OF WEST BRIGHTON, NEW YORK, ASSIGNOR TO WIRED RADIO, INC., OF NEW YORK, N. Y., A CORPORATION OF DELAWARE.

METHOD FOR AMPLIFYING THREE-PHASE HIGH-FREQUENCY POWER.

Application filed February 20, 1926. Serial No. 89,800.

My invention relates broadly to three phase high frequency systems, and more particularly to a system for amplifying three phase high frequency currents and delivering the amplified current to a three phase load.

One of the objects of my invention is to provide an electron tube amplification system for three phase high frequency currents wherein a minimum number of electron tubes are required for increasing the amplitude of three phase current and supplying the amplified current to a load current.

Another object of my invention is to provide a balanced electron tube amplifier system for amplifying the power of all of the phases of a three phase high frequency current source and supplying the amplified power to a three phase load.

Still another object of my invention is to provide a circuit arrangement for the amplification of three phase high frequency currents wherein a pair of balanced electron tubes have their input circuits coupled through open delta connected transformers with a three phase current source, and their output circuits connected through open delta connected transformers with a three phase load for delivering amplified three phase high frequency current to the load.

Still another object of my invention is to provide a three phase high frequency current amplification system wherein open delta connected transformers are arranged to deliver amplified three phase current to a tuned intermediate circuit with various methods of transformation between the intermediate tuned circuit and a three phase high frequency load.

My invention will be more clearly understood from the specification hereinafter following by reference to the accompanying drawings, in which:

Figure 1 is a diagrammatic view illustrating the principle of my invention showing a balanced electron tube amplification system for amplifying all of the phases of a three phase source and delivering the three phase high frequency current to a three phase load; Fig. 2 illustrates one embodiment of the intermediate tuned circuit between the amplified three phase high frequency cur-

rent and the three phase load; and Fig. 3 illustrates a transmission system embodying the three phase high frequency current amplifier of my invention and showing a modulation circuit in connection therewith.

Heretofore in the art of generating and amplifying three phase high frequency power, it has been usual to raise the power level of each phase individually, namely, to employ one amplifier tube or one set of amplifier tubes for each of the three phases. Such systems are disclosed in co-pending applications of Robert D. Duncan, Jr., Serial No. 1,374, filed January 9, 1925, now Patent 1,578,881, dated March 30, 1926; Serial No. 61,019, filed October 9, 1925; Serial No. 65,125, filed October 27, 1925; and others. The chief disadvantage of such systems is the multiplicity of tubes required.

The system of circuits disclosed in the present invention effects amplification of three phase high frequency power with a minimum number of amplifier tubes. I provide a combination of a balanced two tube type of high frequency power amplifier with the so-called open delta connection of transformers for effecting power amplification for use in connection with wired radio transmission over three phase electric power transmission lines.

Referring to the drawings in detail and particularly to Fig. 1, reference character 1 represents a source of three phase high frequency current which may be modulated or unmodulated as the case may be. Connections 2, 3, 4, extend from source 1, the three phases being formed between 2-3, 3-4 and 4-2. Connected respectively between 2, 3, and 3, 4, are primary inductances 5 and 6 of transformers 7, 8. Inductively coupled to primaries 5, 6, are secondary inductances 9, 10. No coupling is assumed to exist between inductance pairs 5-6 and 9-10. Inductances 9-10 are connected in series in the proper manner, the free terminals respectively connecting with grids 11, 12, of tubes 13, 14. The common point of connection of inductances 9, 10, is connected through biasing battery 15 to common filament connection 16 which may be grounded at 17. Plates 18, 19, of tube 13, 14, are interconnected through primary inductances

20, 21, of output transformers 23, 24. The common point of connection is shown connected with the positive terminal of plate battery 22, the negative terminal of which is 5 connected with common filament connection 16. Inductively coupled to primary inductances 20, 21, are secondary inductances 25, 26, which are connected in series. Leads are brought out from the three terminals 10 of inductances 25, 26, which connect through capacities 27, 28, 29, to the three phase electric power transmission line 30. No coupling is assumed to exist between the inductances pairs 20—21 and 25—26.

15 In Fig. 2 variable inductances 31 and 32 are shown connected in series respectively with secondary inductances 25 and 26. Only inductances 25 and 26 are assumed to be coupled with inductances 20 and 21. The 20 three connections to these inductance pairs, as with Fig. 1, contain in series variable capacities 27, 28, 29, and connect with points 33, 34, 35, of the circuit composed of primary inductances 36, 37, 38, of transformers 25 39, 40, 41. Inductances 36, 37, 38 form a closed circuit containing in series variable capacity 42. Inductively coupled to inductances 36, 37, 38, are secondary inductances 43, 44, 45, which are shown connected in 30 Y in the three phase manner. The free terminals of inductances 43, 44, 45 are respectively, connected in series with variable inductances 46, 47, 48, variable condensers 49, 50, 51, to a three phase electric power transmission system not shown.

35 In Fig. 3, 52 represents in entirety a source of unmodulated single phase high frequency current which operates into phase displacing circuit 53 of a type described in copending applications, Serial Nos. 1,374 and 61,019 filed respectively, Jan. 9, 1925 and Oct. 7, 1925. Inductively coupled at transformer 54 are secondary inductances 9, 10, which correspond to like numbered inductances of

40 Fig. 1. As with the circuit of Fig. 1, inductances 9, 10, form the input circuits of amplifying tubes 13, 14, the plate circuits of which are interconnected through series connected inductances 20, 21, capacities 55, 56, 45 and common connection 57. Plates 18, 19, derive their requisite high positive continuous voltage from source 58, here shown to be a D. C. generator negative terminal 50 grounded at 17, through high frequency choke coils 59 and low frequency choke coil 60. Choke coils 59 and condensers 55, 56, function to prevent the passage of continuous current through output inductances 20, 21, and of high frequency alternating 55 current back into 58 and apparatus connected thereto. Connected to the junction between choke coils 59 and 60 are the parallel connected plates of tubes 61 and 62, of 60 which the filaments and grids are also connected in parallel. One filament connected

in grounded at 17. Grids are connected to secondary 65 of microphone transformer 66, and biasing battery 67. The primary circuit of transformer 66 contains the primary winding 68, microphone 69 and battery 70. Inductively coupled to output inductances 20, 21, are secondary inductances 71, 72, each of which is connected in series with variable inductances 73, 74. As before, the three terminals of these secondary inductances are connected to the three conductors of a three phase electric power transmission line 30, through condensers 75, 76, 77. No coupling is assumed to exist between the paired inductances 20, 21, and 75 76 77 80 71, 72.

85 Referring again to the circuit of Fig. 1, which may be considered as typical, it will be observed that three phase high frequency source 1 operates into the primary windings of transformers 7 and 8, of which both the primary and secondary coils are connected in open delta. The same is true with the output transformers 23 and 24 connected in the plate circuits of the tubes. From the fundamental theory of alternating current circuits it will be noted that if, under the proper conditions, the primary coils of two transformers are connected in series across the three conductors of a three phase feeder, i. e., in open delta, the voltages generated between the three terminals of the two secondary coils which are also connected in series or in open delta, and, when properly connected, are displaced in phase by 120 degrees. The circuits of Figs. 1, 3, disclose methods utilizing open delta connected transformers in conjunction with the balanced type of electron tube amplifier for obtaining three phase high frequency power amplification with the minimum number of tubes. The mathematical theory of the operation of the circuits is given in the following:

100 Let V_{g1} and V_{g2} respectively, represent the instantaneous values of the voltages developed in secondaries 9 and 10 and impressed between grid and common filament connection 16 of tubes 13 and 14. Now since transformers 7, 8, are connected in open delta and are supplied from three phase current source 1, V_{g1} and V_{g2} are displaced in phase by 120 degrees. Assuming they are of equal amplitude, they are written in the form

$$(1) V_{g1} = E \sin \omega t.$$

$$(2) V_{g2} = E \sin (\omega t - 120^\circ).$$

105 The law of the electron tube amplifier may be expressed in the usual form

$$(3) i_1 = a (V_p + \mu V_{g1})^2.$$

$$(4) i_2 = a (V_p + \mu V_{g2})^2.$$

110 wherein the terms of instantaneous values for tubes 13, 14, respectively

i_1 and i_2 represent plate currents.

115 V_p represents voltages between plate and common filament connection.

V_{g1} and V_{g2} as defined.
 a and μ are constants of the tubes.

Substituting equations (1) and (2) in (3) and (4), there results

$$(5) \quad i_1 = a(V_p^2 + \frac{\mu^2 E^2}{2} - \frac{\mu^2 E^2}{2} \cos 2\mu t + 2\omega V_p E \sin \omega t)$$

$$(6) \quad i_2 = a(V_p^2 + \frac{\mu^2 E^2}{2} - \frac{\mu^2 E^2}{2} \cos (2\omega t - 240^\circ) + 2\mu V_p E \sin (\omega t - 120^\circ))$$

The fundamental frequency terms of expressions (5) and (6) are, respectively

$$(7) \quad 2\mu V_p E \sin \omega t$$

$$(8) \quad 2\mu V_p E \sin (\omega t - 120^\circ)$$

that is in the primary inductance 20 or between points A—B the instantaneous voltage as given by (7) is developed. And in primary inductance 21, or between points B—C, the instantaneous voltage as given by (8) is developed. Now in a delta connected three phase system in considering the phase relations of the different voltages it is necessary to adopt a given direction in passing through the circuits as positive to give to the various voltages their proper signs in accordance with this assumed positive direction. In Fig. 1, the direction A—B—C—A is assumed to be positive. The voltage between AB is given by expression (7); the voltage between BC is given by expression (8). The voltage between AC is obtained by proceeding from C to A through inductances 20, 21, and is given by

$$(9) \quad -[2\mu V_p E \{\sin \omega t + \sin (\omega t - 120^\circ)\}] \\ = 2\mu V_p E \sin (\omega t - 240^\circ)$$

or the voltages developed respectively between points A—B, B—C and C—A are displaced in phase by 120° as with source 1. The voltages developed in the open delta connected secondaries 25, 26, due to transformer action, are also displaced in phase by 120° and hence, three phase voltages are impressed in transmission line 30.

The next to the last terms of expression (5) and (6) are of twice the fundamental frequency, i. e., are second harmonic terms displaced from each other in phase by 240° . Referring again to Fig. 1, the second harmonic voltage generated in primary 20 or between points AB is given by

$$(10) \quad -\frac{\mu^2 E^2}{2} \cos 2\omega t$$

and in primary 21 or between points BC

$$(11) \quad -\frac{\mu^2 E^2}{2} \cos (2\omega t - 240^\circ)$$

Similar to the fundamental frequency

component voltages, the second harmonic voltage between points AC is

$$(12) \quad -\left[-\frac{\mu^2 E^2}{2} \{\cos 2\omega t + \cos (2\omega t - 240^\circ)\} \right] \\ = +\frac{\mu^2 E^2}{2} \cos (2\omega t - 120^\circ).$$

That is, these voltages also have their phases displaced by 120° , however, the double frequency voltages appearing between points BC and CA respectively lag the double frequency voltage between AB by 240° and 120° instead of by 120° and 240° as is the case with the fundamental frequency components.

Due to transformer action at 20—25 and 21—26, the second harmonic or double frequency voltages will appear in the transmission line 30.

The circuit of Fig. 1 presents a means of amplifying three phase high frequency power with a minimum number of electron tubes.

In Fig. 2 the secondary inductances 25 and 26, each containing a variable inductance 31 and 32 in series, are connected in open delta and operate into inductances 36, 37 and 38, which are connected through variable condenser 42 in closed delta. Inductively coupled to inductances 36, 37, 38, are Y connected inductances 43, 44, 45, which in turn operate into the final load circuit through variable inductances 46, 47, 48, and variable capacities 49, 50, 51. The circuit of Fig. 2 shows a method for transferring at three phase from open to closed delta and then to Y connection, an expedient which has a very practical value.

The circuit of Fig. 3 shows a complete arrangement for obtaining three phase high frequency current from a source of single phase energy, utilizing open delta connected transformer and the balanced double tube type of power amplifier as disclosed in Fig. 1, and showing in addition means for modulating the output of the amplifier tubes. In this figure secondary inductances 9 and 10, connected in open delta, are placed in a rotating magnetic field established by phase displacing circuit 53. Three voltages are

- developed in secondary inductances 9 and 10 which are displaced 120° in phase, as explained with reference to Fig. 1. In the circuit of Fig. 3, the continuous voltage for the plates of the balanced amplifier tubes 13, 14, is supplied in parallel with the plates and the load circuit 55—20—21—56. The modulator tubes 61, 62 with associated microphone circuits effect modulation of the high frequency output of the tubes 13, 14, through the action of iron core inductance 60. Plate modulation is shown in Fig. 3 although it will be understood that grid modulation may be employed, and it is not intended to so limit the scope of this invention. Secondary inductances 71, 72, containing variable inductances 73 and 74 in series, are connected in open delta and operate into the three phase transmission line 30.
- While I have described certain preferred embodiments of my invention, I desire that it be understood, that modifications can be made and that I intend no limitations upon the invention other than are imposed by the scope of the appended claims.
- What I claim and desire to secure by Letters Patent of the United States is:
1. In a system for amplifying three phase high frequency power, the combination with a source of three phase high frequency current, a pair of electron tubes connected in balanced relationship, input and output circuits for said tubes, an open delta transformer system connected in said input circuits for impressing energy from said source upon said electron tubes, a load circuit, and means for impressing three phase high frequency current derived from said output circuits upon said load circuit.
  2. In a system for amplifying three phase high frequency current, the combination of a source of three phase high frequency current, a pair of electron tubes having input and output circuits connected in balanced relationship, open delta connected transformers coupling said input circuits with said source of high frequency current, a load circuit, and open delta connected transformers interposed between said output circuits and said load circuit for impressing three phase high frequency current upon said load circuit.
  3. In a system for amplifying three phase high frequency current, the combination with a source of three phase high frequency current, a pair of balanced electron tube circuits, a load circuit, and means connected between said electron tubes and said load circuit for impressing three phase high frequency current upon said load circuit, said electron tube circuits operating to increase the amplitude of said three phase high frequency current.
  4. In a system for amplifying three phase high frequency power, the combination with

a source of three phase high frequency current of a pair of balanced electron tube circuits, each including input and output circuits, open delta connected transformers coupling said input circuits with said source, open delta connected transformers connected with said output circuits, a load circuit, closed delta transformers arranged in circuit with said last mentioned transformers, and connections between said closed delta transformers and said load circuit for delivering amplified three phase high frequency current to said load.

5. In a system for amplifying three phase high frequency current, the combination with a source of three phase high frequency current, a balanced electron tube system including a pair of electron tubes, each having input and output circuits, open delta connected transformers coupling said input circuits with said source, a load circuit, and a composite open and closed delta transformer system coupling said output circuits with said load circuit for delivering amplified three phase high frequency current to said load circuit.

6. In a system for amplifying three phase high frequency current, the combination with a source of three phase high frequency current, a pair of electron tubes connected in balanced relationship, said tubes having input and output circuits, open delta connected transformers interposed between said source and the input circuits of said electron tubes, a load circuit, an intermediate tuned circuit connected with said circuit, and delta connected transformers coupling said output circuits with said intermediate tuned circuit for impressing three phase high frequency current upon said load circuit.

7. In a system for amplifying three phase high frequency current, the combination with a source of three phase high frequency current, a pair of electron tubes connected in balanced relationship, said tubes having input and output circuits, a source of three phase high frequency current, open delta connected transformers interposed between said source and the input circuits of said electron tubes, a load circuit, open delta connected transformers connected in the output circuits of said electron tubes, an intermediate circuit connected with said delta connected transformers, and a Y connected system for establishing connection between said intermediate circuit and said load circuit for impressing three phase high frequency current upon said load circuit.

8. In a system for amplifying three phase high frequency current, the combination with a source of three phase high frequency current, a pair of electron tubes connected in balanced relationship, said tubes having input and output circuits, a source of three

- phase high frequency current, open delta connected transformers interposed between said source and the input circuits of said electron tubes, a load circuit, open delta connected transformers connected in the output circuits of said electron tubes, open delta connected transformers interposed in the output circuits of said electron tubes, an intermediate circuit connected with said last mentioned open delta connected transformers, an additional set of transformers having their primary windings connected in closed delta to said intermediate circuit and their secondary windings connected in Δ to said load circuit for impressing three phase high frequency current upon said load circuit. 5
9. In a system for amplifying three phase high frequency current, the combination with a source of three phase high frequency current, a pair of electron tubes each having grid, filament and plate electrodes, a pair of input circuits connected between the grid and filament electrodes of each of said tubes, 20 a pair of output circuits connected between the plate and filament electrodes of each of said tubes, an inductance included in each of said circuits, a pair of inductances coupled with the inductances in said input circuits, and connections between said last men- 25
- tioned pair of inductances and said source of three phase high frequency current, a load circuit, an intermediate tuned circuit connected with said load circuit, and a pair of inductances connected in said intermediate circuit and coupled respectively with the inductances in the output circuits of said electron tubes whereby amplified three phase high frequency current may be impressed upon said load circuit. 30
10. In a system for amplifying three phase high frequency power, the combination of a source of three phase high frequency current, a pair of electron tubes each having filament, grid and plate electrodes, 35 input circuits comprising a pair of transformers with primary and secondary windings connected in open delta for associating said grid electrodes with said source, output circuits comprising a pair of transformers 40 with primary and secondary windings connected in open delta associated with said plate electrodes, a three phase electric power distribution circuit constituting a load circuit and connections between said load circuit and said output circuits for impressing amplified three phase high frequency current on said load circuit. 45
